US00D879526S

(12) **United States Design Patent** (10) **Patent No.:** **US D879,526 S**
Abadie et al. (45) **Date of Patent:** **** Mar. 31, 2020**

(54) **CHAIR BACK**

(71) Applicant: **Gary Platt Manufacturing, LLC**,
Reno, NV (US)

(72) Inventors: **Edmond E. Abadie**, Reno, NV (US);
Daniel J. Waller, Reno, NV (US)

(73) Assignee: **GARY PLATT MANUFACTURING, LLC**,
Reno, NV (US)

(**) Term: **15 Years**

(21) Appl. No.: **29/687,984**

(22) Filed: **Apr. 17, 2019**

Related U.S. Application Data

(60) Continuation of application No. 29/660,998, filed on Aug. 23, 2018, now Pat. No. Des. 847,549, which is a division of application No. 29/561,747, filed on Apr. 19, 2016, now Pat. No. Des. 829,458.

(57) **CLAIM**

The ornamental design for a chair back, substantially as shown and described.

DESCRIPTION

A portion of the disclosure of this patent document contains material for which a claim for copyright is made. The copyright owner has no objection to the facsimile reproduction by anyone of the patent document or the patent disclosure, as it appears in the US Patent and Trademark Office patent file or records, but reserves all other copyrights whatsoever.

FIG. 1 is an upper perspective view of an ornamental design for a chair back;

FIG. 2 is a right elevation view thereof;

FIG. 3 is a left elevation view thereof;

FIG. 4 is a front view thereof;

FIG. 5 is a rear view thereof;

FIG. 6 is a top view thereof; and,

FIG. 7 is a bottom view thereof.

In the drawings, the broken lines depict portions of the gaming chair that form no part of the claimed design.

1 Claim, 4 Drawing Sheets
